UNITED STATES PATENT OFFICE.

WARREN W. CARPENTER, OF QUEENS, NEW YORK, ASSIGNOR TO WESTERN ELECTRIC COMPANY, INCORPORATED, OF NEW YORK, N. Y., A CORPORATION OF NEW YORK.

TELEPHONE-EXCHANGE SYSTEM.

Application filed June 30, 1924. Serial No. 723,140.

This invention relates to telephone exchange systems and more especially it has to do with telephone systems of the class wherein automatic switching apparatus is employed either entirely or in part for the establishment of conversational connections.

In systems where recording senders are located at the central office for receiving records from calling subscribers' lines or from operators' positions to, in turn, exercise a control over the operation of a series of selective switches, it is found that the efficiency and speed of operation may be enhanced by providing a number of controlling mechanisms or markers also situated at the central office and separate from the recording senders. A part of the duties ordinarily performed by the senders are delegated to these markers, which receive a portion of the record from the senders to which they are connected and thereupon govern the selective operation of one or more of the switches. Other markers are subsequently associated with the senders and in their turn govern succeeding switches to further extend the connection. These markers being equivalent are arranged so that any sender may select any one of the markers, according to their busy or idle condition at the time. The markers are also common to a number of selective switches at one or more switching stages and each may be associated with any switch for the purpose of controlling the same.

It is during the period that a marker is attached to a sender and to a selective switch that a substantial portion of the operations, incident to the setting of the switch, take place. In other words the various sequential operations which go to make up the selecting, testing and seizing at the selective switch are accomplished under the control of the marker and while it is attached. Due to the wide latitude which the marker has in its association with other pieces of apparatus, and owing to the comparatively large number of sequential operations which comprise the total function of the marker, it is particularly desirable, in the event the marker encounters trouble, to ascertain the relation of the marker to the other apparatus and the point to which it has progressed at the time of the trouble.

The object of the invention is, therefore, to obtain information showing the association of a switch controlling mechanism with other apparatus and also showing the point to which such mechanism has progressed when it encounters trouble.

A feature of the invention relates to a trouble indicating device common to a number of switch controlling markers which become associated with a marker which has encountered trouble and serves to indicate the identification of the marker, its relation to other apparatus and also the progress of the marker.

Another feature relates to a timing device which becomes effective after a measured interval, in case the marker has ceased to function normally, and causes such marker to become automatically associated with the trouble indicator.

This invention is in the nature of an improvement on the system shown and described in the application of W. W. Carpenter, Serial No. 703,362, filed April 1, 1924, and a general reference is hereby made to said application for an understanding of the manner in which the various parts of the present system are arranged and the details of operation wherever such arrangements and details are hereinafter mentioned but are not particularly illustrated or described.

The drawing, which is partly diagrammatic and partly in full detail, illustrates the circuits and apparatus in a local telephone office. The equipment shown is capable of receiving calls from subscribers' lines which terminate as calling lines in the local office and of completing these calls to any of the subscribers' lines which terminate as called lines in the same office. Moreover, it is designed to complete calls to the various types of operators' positions as customarily employed in commercial exchanges. Furthermore, the equipment and apparatus shown in this disclosure is designed to extend calls from the local office over outgoing trunks to the various types of outlying offices with which connection may be desired. Again, it is prepared to receive calls incoming from outlying offices and to complete them to local subscribers' lines. For the purpose of this case, however, it has

been considered sufficient to confine the description to local office working and to point out only in a general way the manner in which interoffice connections are effected.

Referring to the drawing Figs. 1 to 28 when taken in the order illustrated in Fig. 31, disclose circuits and apparatus employed in the establishment of connections between calling and called lines.

Fig. 1 illustrates diagrammatically a coordinate line switch in which the calling lines appear and also a coordinate sender selector switch.

Fig. 2 illustrates a portion of a coordinate district selector switch in which terminate the trunks leading from the line switches.

Fig. 3 shows one of the coordinate office selector switches in which terminate the trunks leading from the district selector and the trunks from which lead to the distant offices.

Fig. 4 shows control circuits associated with one of the trunks leading from the district selector switch.

Fig. 5 illustrates a portion of a coordinate incoming selector switch in which terminate trunks from the district switches.

Fig. 6 illustrates a number of trunks leading from the incoming selector switches to the final connectors.

Fig. 7 illustrates a portion of one of the final connector switches which have access to the called subscribers' lines.

Fig. 8 illustrates a portion of one of a plurality of register senders.

Fig. 9 illustrates a connecting device for connecting the senders to the outgoing markers.

Figs. 10 to 14, inclusive, illustrate one of the outgoing markers.

Fig. 10 shows the register relays for receiving the record from the senders.

Fig. 11 shows the translator.

Fig. 12 shows the routing relays.

Fig. 13 illustrates the time measuring mechanism for controlling the release of the outgoing marker.

Fig. 14 shows a portion of the testing relays and also the marker control relays.

Fig. 15 illustrates the frame connectors and trunk connectors for associating the markers with the district frames and trunks, respectively.

Fig. 16 illustrates a frame and trunk connector for associating the markers with the office frame and outgoing trunks, respectively.

Fig. 17 shows a connector for connecting the trouble indicator to the markers.

Fig. 18 illustrates the trouble indicator.

Fig. 19 illustrates a sender connector for connecting the register senders with the incoming markers.

Figs. 20, 21, 23 and 24 illustrate one of several incoming markers.

Fig. 20 shows the numerical register relays for receiving the registration of the senders.

Fig. 21 shows the incoming marker translator.

Fig. 22 shows the connecting device for associating the incoming marker with one of a number of final translators.

Fig. 23 shows the testing relays and also certain control relays in the incoming marker.

Fig. 24 illustrates the incoming frame connectors, for connecting the incoming markers to the incoming switches and also a time measure device.

Fig. 25 shows the connecting device for associating the incoming markers with the groups of trunks leading from the incoming to the connector switches.

Fig. 26 shows a portion of one of the final translators and also a connecting device for associating the same with final or connector switches.

Fig. 27 shows a connector for connecting the trouble indicator to the incoming markers.

Fig. 28 shows the trouble indicator for the incoming markers.

Figs. 29 and 30 taken together comprise a diagram showing the relative disposition of the various parts of the complete system.

General description of the system and apparatus.

Referring first to Figs. 29 and 30, descriptions will be given of the general plan of the system. The lines 2900 enter the office and terminate in a number of line switches, such as switch 2901. Outgoing from these switches are a number of trunks which extend to district selectors. For reasons which will appear hereinafter, the district selector switches are divided into a number of groups, two of which groups 2906 and 2907 are illustrated. The group 2906 comprises a number of district selector frames, two of which, 2908 and 2909 are shown, and trunks such as the trunks 2904 and 2905 leading from the line switches are distributed among these district selectors. In like manner, other trunks 2902 and 2903 extend to the district selectors 2910 and 2911 of the second group 2907. Other groups may be provided.

The trunks outgoing from the district selector switches lead in different directions. For example, some of the trunks 2923 and 2925 extend to office selector switches. The office selectors may be arranged in groups similar to the district switches, the selector 2927 being of one group, and the selector 2928 being of a second group of office selectors. The trunks 2932 leading from the office selectors extend to distant offices to take care of the interoffice traffic.

Other trunks leading from the district se-

lector switches, such as the trunks 2922 and 2924 extend to incoming switches located in the same central office.

These incoming switches are divided into two groups, group 3000 comprising the switches 3002 and 3003 and group 3001 comprising the switches 3004 and 3005. The trunks outgoing from the incoming switches, such as trunks 3012 and 3013 lead to the various connector switches of the several groups. Only one group of connector switches 3014, which includes the switches 3015 and 3016 is illustrated in the drawing. The connector switches have access to the called lines as 3017 and 3018.

The trunks which lead from the line switch to the district selectors also appear in the sender selector switches 2912 which operate to extend these trunks to the register senders. Two of these senders 2913 and 2914 are shown. The sender connector may comprise a plurality of sections 2915, 2916, etc., which serve to connect the senders to the outgoing markers 2917 and 2918. While only two of the markers are illustrated, any suitable member may be provided.

In order to connect the markers to the district frames, there are provided a number of frame connectors, one for each group of district selector frames. Frame connector 2919, for instance, serves to connect any of the markers to any of the frames in the selector group 2906. Likewise the frame connector 2920 serves to connect any of the markers to any of the frames in the district selector group 2907.

The outgoing markers are connected to the trunks outgoing from the district switches by means of trunk connectors 2921, 2933, etc.

In a similar manner frame connectors 2929 and 2930 are provided for associating the outgoing markers respectively with the office selector switches of the two corresponding groups, while trunk connectors such as the trunk connector 2931 are provided for associating the outgoing markers with the groups of trunks leading from the office switches.

A sender connector device which may comprise a plurality of sections 3008 and 3009 serves to connect the senders with any one of a plurality of incoming markers, two of which 3010 and 3011 are shown. These incoming markers are associative through frame connectors 3006 and 3007 respectively with the groups of incoming selector frames 3000 and 3001.

A number of final translators 3019 and 3020 are provided. There may be any desired number of these translators, each one pertaining exclusively to a different portion of the subscribers' lines as called lines. Any of the final translators may be associated with the incoming markers.

The final translator, 3019 for example, is arranged to make connection with any of the final connector switches of the group 3014 and serves to control any one of these switches to make connection to the called subscriber's line. In a similar manner, the final translator 3020 is associative with the connector switches of a different group, and governs the same to extend connections to other called subscribers' lines.

A trouble indicator 2950 is provided in common for all outgoing markers 2917, 2918, etc., and may be associated with any marker in case of trouble. Similarly a trouble indicator 3050 is provided for the incoming markers 3010, 3011.

Referring to Figs. 1 to 28 a more detailed explanation will now be given of the general arrangement of the switches and controlling mechanism. First, with respect to the construction of the line switch, selector switches, the connector switch, and the sender selector, these may be of the same general construction and operation as the switches shown and described in detail in the application of S. B. Williams, Serial No. 596,179, filed October 23, 1922, Patent No. 1,517,331, granted Dec. 2, 1924.

The subscribers' lines appear in the line switches as shown in Fig. 1 of the drawing, there being a plurality of lines assigned to each vertical row of contacts. The line 105 is capable of connection with each of a plurality of link circuits, or horizontal links, as they will be called hereinafter. In like manner, other lines of the same vertical row have access to other horizontal groups not shown in the drawing. There may be any desired number of vertical rows or groups of lines. The outgoing trunks such as trunk 102 are illustrated and occupy each a complete vertical row of contacts in the line switch 100 thus intersecting all horizontal links in the switch.

The trunks outgoing from the line switches lead to the district selector switches 200 appearing in vertical rows 201, 202, etc. These trunks may be disposed in any convenient manner among the different district selectors of the different groups.

The trunks extending between the line switches and district selectors also appear in the sender selector switch 106. These trunks appear in the sender selector switch in substantially the same manner as the subscribers' lines appear in the line switches.

The outgoing circuits from the sender selector switch each lead to separate recording sending mechanisms, and each such circuit occupies a full vertical row of contacts. The circuit 112 occupies the vertical row 113 and leads to the particular recording sender shown in the drawing.

The purpose of the register sender shown in Fig. 8 is to receive and record the design.

nation of desired lines. The receiving portion of the sender consists of the impulse relays which receive the impulses and in turn operate a series of registers 800, 801 shown 5 schematically. The first three registers 800 may comprise three sets of relays and are for the purpose of recording the three digits which constitute the code designation of the office in which the call is to be completed. 10 The remaining registers 801 are similarly constituted and serve to receive and record the numerical and stations portions of the called line designation.

As soon as the sender has received the 15 record from the calling line, it is connected through the sender connector 900 to an idle outgoing marker and the office or code part of the designation is transferred from the register 800, through the sender connector 20 900 to corresponding registers 1000, 1001 and 1002 in the marker.

The register 1000 determines the operation of one of a number of multi-contact relays 1102 and 1103, etc. The register 1001 25 determines the operation of one or more of the relays 1104, 1105, 1106. With these relays operated, the register 1002 applies ground potential to one or more of the conductors 1113 which lead through the trans- 30 lator device 1100 and to the distributing frame 1213, causing the operation of one or more of the routing relays 1200.

As hereinbefore noted, there are a number 35 of frame connecting devices for connecting the outgoing markers to the district and office frames. There is one of these district frame connectors for each of the different groups of district frames, the purpose being to enable a number of different markers to 40 be simultaneously connected to district switches in the different groups. The district frame connector 1500 is individual to the particular group of district frames, which contains the district switch 200. The 45 connector 1500 consists of a number of multi-contact relays 1506, 1507, etc., each individual to a different one of the outgoing markers. Moreover, it includes a number 50 of multi-contact relays 1508, 1509, etc., each of which is individual to a different district selector in the group. The relay 1506 is seen to be individual to the particular marker shown in the drawing, and relay 1509 is individual to the particular district switch 55 200 shown. Obviously other relays may be provided for additional switches and markers.

A second one of the district frame connectors 1501 is illustrated diagrammatically 60 in the drawing. It has a plurality of relays each individual to one of the outgoing markers, and also relays each individual to the different selectors of a second group of district frames.

In addition to the district frame connec-

tors, there are provided a number of district trunk connectors, one of which, 1502, is shown partly in detail, and a second of which, 1503, is illustrated diagrammatically. These trunk connectors serve to associate the 70 outgoing markers with the different groups of trunks outgoing from the various district selector switches.

For connecting the outgoing markers to the office selector frames in the event of 75 interoffice connections, a plurality of office frame connectors are also employed. One of these, the frame connector 1600 is shown, serving to connect any of the outgoing markers to the different office selector 80 switches of a given group. One of the office selector switches 300 of this particular group is shown. As in the case of the district frame connectors, other office frame connectors may be provided, each serving to connect the markers to the different office frames of the other groups.

Furthermore, office trunk connectors, such as the trunk connector 1601 are provided for connecting the outgoing markers to the 90 different groups of trunks outgoing from the office frames.

Each of the outgoing markers is equipped with a series of testing relays 1400 for testing the horizontal links and the outgoing 95 trunks on any of the district or office switches. Each relay has two windings, one for testing the condition of the corresponding link on any switch frame, and a second winding for testing the trunk having access 100 to such link. There are, therefore, as many testing relays in the series as there are such links and trunks in any vertical row in the switch frames.

Inasmuch as the present case is devoted 105 more particularly to the establishment of a local connection, the routing of calls through the office selector switches 600 will only be taken up in a general way. It will be noted that the trunks which reach the office 110 selectors appear in the district frame multiples. These trunks occupy the full vertical rows 302, etc., of the office selector 300, being accessible to all horizontal links 305, 306, 307 and 308. The trunks occupying the vertical 115 rows 303, 304, etc., comprise groups which extend to distant offices for carrying the interoffice traffic.

For the purpose of local calls, the connections are extended from the district selectors 120 directly to an incoming selector switch 500.

The incoming selector frame is divided into a number of sections, two of which are 125 partially illustrated. Each of these three sections may comprise a number of horizontal link circuits. The incoming trunks appear in the rows 501, 502, etc., each trunk having access to all the horizontal links in only one section. The trunk 217, for instance appears in the vertical row 502, and 130

is accessible to the links of the section 514.

A number of groups of trunks leading from the incoming switches extend and appear in the vertical rows of the final or connector switches 700. The connector switches 5 may be arranged in a number of groups, each group of which has access to the corresponding group of called subscribers' lines. In order to reach any desired group 10 of connectors, it is only necessary to select at the incoming switch a group of trunks extending from the incoming switches to the proper group of connectors. These groups of trunks, it will be noted, are multiplied 15 so as to have an appearance in each of the horizontal sections 514, etc., of the incoming switches.

Furthermore, it will be noted that the connector switches are divided into a number 20 of horizontal sections. In this case there are five horizontal sections, each comprises a number of horizontal connecting links and a single horizontal testing link. Two of these sections 714 and 715 are illustrated. 25 As in the case of the incoming switches, each of the trunks of a group has a single appearance in each of the five sections of the connector switches.

For the further purpose of description it 30 will be assumed that a group of connectors has access to a group of 1000 called subscribers' lines. Accordingly, for a 10,000 line office there will be 10 of these connector groups, and each group may have as many 35 switches as are necessary to serve the full 1,000 lines, together with provision for P. B. X. trunks.

The called subscribers' lines appear in the connector switches in vertical rows 703, 704, 40 etc., each vertical row accommodating five subscribers' lines. The line 716, for example, appears in the row 703, and has access to all of the horizontal links in the section 714. A decimal group of ten subscribers' lines therefore, must occupy two vertical 45 rows in the connector switch, five on each row.

After the connection has been extended through the district selector switch over a 50 trunk to the incoming selector 500 and the outgoing marker is disconnected from the sender, the sender is immediately connected through the sender connector 1900, to an idle incoming marker. The incoming marker 55 comprises a number of numerical registers, 2000, 2001, 2002, 2003 and 2004 which receive the numerical designation from the sender. Also the marker includes a translator device 2100 which is set in accordance 60 with the operation of the numerical registers.

The next function to take place is to connect the incoming marker to one of the final translators. Under the present assumption, 65 there being 10 final groups of connector

switches and called lines, there should also be 10 final translators, one for each of the different connector groups. For the purpose of connecting the incoming markers to the final translators, there are provided a 70 number of connecting devices as shown in Figs. 22 and 25. One of these connecting devices 2200 serves to connect the markers to the particular final translator illustrated. Another connecting device 2201 shown dia- 75 grammatically serves in a similar manner to connect the incoming markers to a second of the final translators. The final translator 2600 is positioned from the numerical registers in the marker, and then cooperates 80 with these registers to select a vertical operating magnet 713 on one of the connector switches in the connector group which relates to the vertical row of contacts in which appears the called line. 85

The incoming markers are associated with the incoming frames by means of frame connectors 2400 and 2401, each of these being individual to a different group of incoming frames. Moreover, the incoming 90 markers are associated with the trunk group leading from the incoming switch to the final connector group by means of a connecting device 2501. Another of these 95 connecting devices 2503 acts in a similar manner to associate the markers with the group of trunks leading to another final connector group. In order to test the horizontal links of any given section in the connector switches and to operate a desired 100 horizontal magnet, there are provided the connecting devices 2500 and 2502. The device 2500 comprises a number of relays 2504, 2505, each individual to a different incoming marker, and a number of relays 105 2506, 2507, each relating to a different one of the horizontal sections 714, 715 etc. The device 2601 comprises a series of relays 2609, 2610, etc., each of which is individual 110 to a different one of the connectors in the group. The schematic 2502 represents another connecting device relating to a second 115 group of connector switches.

Detailed description of the operation.

115

Establishment of a local connection.—Assume that the subscriber of line 105 desires to hold a conversation with the subscriber of line 716 located in the same office. Consider that the code or office designation of the local office is represented by the abbreviation T. O. K., which in terms of dial impulses is represented by three digits 8, 120 6 and 5. Assume further that the numerical designation of the line 716 is 2345. 125

The calling subscriber on removing his receiver from the switchhook, causes the operation of the line switch 100 to extend the line 105 to an idle trunk 102. The initiation of the call also causes the operation 130

of the sender selector 106 to select an idle sender.

During the operation of the sender selector switch 106 the relay 107 is operated resulting in the extension of the calling line 105 to the impulse relay 802 and balance coil 803 in the sender.

The calling subscriber now operates his dial to send three series of impulses representing the office code which are recorded on the office registers 800 and four series representing the numerical part of the designation which are recorded on the registers 801.

15 *Connection of the recording sender to an idle outgoing marker.*—At the time the third series of impulses representing the last code letter of the office designation is received, and recorded on the register 800, 20 the operation of the sender connector shown in Fig. 900 is initiated for the purpose of connecting the sender to an idle outgoing marker. For this purpose relay 907 is operated in a circuit from ground, through 25 the lower back contact of relay 908, right contact of relay 909, upper winding of relay 907, conductor 917, to battery in the sender. Relay 907 operates, and locks through its lower winding and contact and 30 the winding of relay 908 to ground. Relay 908 operates and prevents any other sender in the same group having access to the markers through the connector 900 since the operating circuit for relays corresponding 35 to the relay 907 is opened.

Relay 907 operates the multi-contact relay 901 individual to the sender shown, in a circuit from battery through the winding of said latter relay, uppermost contact of 40 relay 907 to ground at the lower front contact of relay 908. If the marker shown is idle the make-busy relay 914 is deenergized and relay 907 in operating operates the relay 915. The circuit for this purpose may 45 be traced from battery through the inner upper contact of relay 907, contact of relay 913, contact of relay 914, front contact of the multi-contact relay 901, thence through the lower back contact of relay 914, 50 lower winding of relay 915 to ground at the contact of the common relay 916. Relay 916 locks in a circuit from ground through the winding of relay 916, upper front contact and upper winding of relay 55 915 and thence to battery through the contact of relay 907. Relay 916 operates in this circuit and causes the operation of the multi-contact relay 906 which represents the marker illustrated in the drawing. The 60 circuit for relay 906 leads from battery through the winding of said relay, inner lower contact of relay 915 to ground at the outer front contact of relay 916. Relay 916 also closes an obvious circuit for the 65 make-busy relay 914 to render the marker

non-selectable by other senders. Moreover, relay 916 operates the relay 913 in a circuit from battery through the winding of relay 913 lowermost contact of relay 915 to ground at the inner contact of relay 916. 70 When relay 906 operates it closes a circuit for the relay 909 traceable from battery through the right winding of said latter relay, contact of relay 906, thence to ground at the lower front contact of relay 908. Relay 909 at its right contact removes ground potential from the winding of relay 907 and all other corresponding relays to prevent the operation of any one of these by another calling sender, even though the relay 908 may be released. With the multi-contact relays 901, and 906 operated as explained, the conductors from the register sender are extended through the sender connector to the selected outgoing marker. 80

Immediately that the sender is connected to the marker relay 1108 is operated in a circuit traceable from ground through the winding of said relay, conductor 1180, contacts of the connector 900, conductor 920 to ground in the sender. Relay 1108 initiates the transfer of the record from the registers 800 of the sender to the corresponding registers 1000, 1001, 1002 of the marker. 90

Transfer of office record from sender to 95 the outgoing marker.—Relay 1108 completes a circuit from ground through its outer right contact, left back contact of relay 1109, back contact of relay 1111, conductor 1114, contacts of connector 900, conductor 100 936, thence through the inner right back, contacts of all the unoperated relays of registers 800 in parallel over conductors 837, 838 and 839, through the connector 900, and thence through the windings of the relays of registers 1000, 1001 and 1002 to battery. These latter relays all operate and close a series circuit for operating relay 1110. This circuit may be traced from battery through the winding of the latter relay, and thence through contacts of all the marker register relays in series to ground at the left contact of relay 1011. Relay 1110 locks to the grounded conductor 1115, and operates the relay 1111. Relay 1111 in 110 turns operates the relay 1112. Relay 1111 at its back contact opens the circuit above traced for operating all of the register relays in the marker. These relays thereupon release, with the exception of those relays which correspond to the operated relays in the registers of the sender. For the particular office designation dialed it may be assumed that relays 1003, 1004, 1006, 1007, 1010 and 1014 remain energized. 120

The next step is to operate the translator 1100 from the register relays in the marker to select one or more of the routing relays shown in Fig. 12. These routing relays each relate to a different one of the groups 125 130

outgoing from the district and office selector switches. In the present case, which involves a local call, it is necessary to select a group of trunks extending from the district selectors to the incoming selector switches. Inasmuch as a total group may be divided into two subgroups, there are provided two routing relays relating to the total group, each individual to a separate subgroup. It may be assumed that the routing relays 1204 and 1205 are assigned to the group of trunks to be employed for this connection. Accordingly, both of these relays will be prepared for operation, but as will be seen later, only the particular one, which is individual to the subgroup of trunks appearing in the district selector 200 will be operated, inasmuch as the other subgroup of trunks will not be concerned for this particular connection.

The register 1000 with the setting given causes the operation of the multi-contact relay 1103 in a circuit from battery through the winding of said relay, thence through the inner right front contact of relay 1004, outermost right contact of relay 1006, inner right front contact of relay 1003, conductor 1017, contact of relay 1112 to the grounded conductor 1115. The register 1001, with the setting given, causes the operation of relay 1106 in a circuit traceable from battery through the winding of said relay, thence through the inner right back contact of relay 1008, outermost right contact of relay 1010, inner right front contact of relay 1007 to the grounded conductor 1017. With the translator 1100 set, a circuit is completed from the grounded conductor 1017, through the inner right back contact of relay 1011, middle right contact of relay 1014, inner right back contact of relay 1013, outer right back contact of relay 1012, conductor 1116, contact of relay 1106, contact of relay 1103, conductor 1117, through the distributing frame 1213, and thence to one terminal of each of the windings of relays 1204 and 1205. As will be seen hereinafter, the other terminal of one of these windings will have battery connected thereto at the proper time.

Operation of district frame connector and connection of the outgoing marker to the district selector.—While the foregoing operations have been taking place, the outgoing marker has also been in the act of associating itself with the proper group of district selector frames by means of a corresponding one of the frame connectors 1500 and 1501. The instant the sender is connected to the outgoing marker, the district frame connector relay 1409 is operated. This relay relates to the frame connector 1500, and when operated instructs the marker that it must use that particular frame connector for reaching the proper group of district

selectors. The other frame connector relay 1410 similarly relates to the frame connector 1501. The circuit for relay 1409 may be traced from ground in the sender, conductor 814, through the sender connector 900, conductor 1018, winding of relay 1409 to battery. Relay 1409 operates the relay 1504, which is individual to the marker shown. The circuit for this purpose may be traced from battery through the inner left contact of relay 1108, conductor 1118, right contact of relay 1402, contact of relay 1409, right winding of relay 1504 to ground at the contact of relay 1505. Relay 1504 operates and locks in a circuit through its left winding and locking contact, left back contact of relay 1520, winding of relay 1505 to ground. Relay 1505 also operates and prevents any other marker from appropriating the frame connector 1500. Relay 1505 closes an obvious circuit for the multi-contact relay 1506 which extends the various leads from the marker through to the grid wires of the connector 1500.

At this time, the vertical operating magnet 210, individual to the row of contacts 201 in the selector 200 in which appears the trunk 102, is operated. The circuit for this purpose may be traced from battery through the winding of said magnet, conductor 218, right outer contact of relay 115, upper front contact of relay 107, thence over conductor 116, through the sender selector switch 106, thence over conductor 816, through the sender connector 900, conductor 1019, inner left back contact of relay 1406, conductor 1432, inner right contact of relay 1504 to ground at the front contact of relay 1505. It will be noted that the relay 1411 also operates in parallel with the vertical magnet 210. Magnet 210 prepares the contacts in the vertical row 201. Magnet 210 also operates the multi-contact relay 1509, individual to the switch 200, in a circuit from battery through the winding of said relay, inner front contact of magnet 210, and thence over conductor 218 to ground as above traced. Relay 1509 connects the grid wires of the frame connector 1500 to the conductors leading to the switch 200. With the frame connector 1500 operated, the vertical magnet 210 and relay 1509 are locked in parallel circuits extending through the frame connector, thence over the conductor 1521, conductor 1433, left contact of relay 1403, conductor 1020, to ground at the contact of relay 1108.

Relay 115 is also operated at this time in a circuit from battery through its left winding, conductor 117, lowermost contact of magnet 210, contacts of frame connector 1500 to ground.

Since the multi-contact relays 1508, 1509, etc., are each individual to a district selector switch 200, the identity of these

switches may be established in the frame connector 1500, for the purpose of determining which one of the routing relays shown in Fig. 12 should be operated. It will be recalled that in the present case, both relays 1204 and 1205 were prepared for operation. Only one of these however, is needed, which is the one that is individual to the group of trunks appearing in the district selector frame 200. Accordingly the relay 1509 has certain of its contacts arbitrarily wired to ground, one of which identifies the district selector frame 200. Accordingly, relay 1211 is operated in a circuit traceable from battery through the winding of said relay conductor 1250, through contacts of the frame connector 1500 to ground. Relay 1211 completes a circuit for operating the routing relay 1205 to the exclusion of relay 1204. This circuit may be traced from battery through the middle contact of relay 1211, thence through the winding of relay 1205, and over the circuit previously traced to ground.

Operation of the district trunk connector to connect the outgoing marker to the group of trunks.—Now that the routing relay 1205 has been selected and operated, the necessary information is available for telling the marker to which group of trunks leading from the district frames it should make connection. As will be seen presently, the trunk connector 1502 is the one employed for connecting the marker to this trunk group. First, the relay 1511 which is individual to the selected marker, is operated by means of a circuit from ground through the back contact of relay 1512, right winding of relay 1511, conductor 1522, inner right contact of relay 1205, conductor 1214, contact of relay 1411, right contact of relay 1402, and thence to battery over conductor 1118 as previously traced. Relay 1511 locks through its left winding to ground in series with the winding of relay 1512 and relay 1512 also operates. Multi-contact relay 1513 is operated next in a circuit through contacts of relay 1511 and 1512. Relay 1513 connects the various conductors from the marker to the common grid wires of the trunk connector 1502.

The next step is to operate the particular one of the multi-contact relays 1515, 1516, etc., which represents the group of trunks to which the marker is to be connected. In the present case, the group of trunks appearing in the vertical row 203 of the district selectors is represented by the relay 1516 and this relay is operated directly from a contact of the routing relay 1205 in the marker. The circuit therefor may be traced from battery through the winding of relay 1516, conductor 1523, outer right contact of relay 1205, conductor 1215, to ground through contacts of relays 1511 and 1512.

Relay 1516 connects the grid wires of the connector 1502 to the conductors leading to the test conductors of the several trunks in the proper group.

Since the multi-contact relay 1516 is individual to row of contacts 203, its operation may be made to cause the operation of the vertical magnet 212. The circuit for this purpose may be followed from ground, through a contact of relay 1516, thence 70 through a contact of relay 1513, conductor 1525, right contact of relay 1408, conductor 1434, middle right contact of relay 1205, conductor 1216, through the frame connector 1500, thence through the winding of magnet 80 212 to battery. Magnet 212 prepares the contacts in the vertical row 203 and also operates relay 1406 in the marker. The circuit for relay 1406 may be completed from ground, through the contact of magnet 212, 85 through the frame connector 1500, conductor 1527, winding of relay 1406 to battery. Relay 1406 locks through its inner right contact to the grounded conductor 1020.

The marker has thus been connected to the district frame and the trunk group outgoing therefrom and the apparatus is now in condition to test the horizontal links in the district switch and the corresponding outgoing trunks. Assuming the first horizontal link 206 to be busy, a ground potential will exist on the sleeve conductor thereof and testing relay 1420 operates in a circuit from battery, through its right winding, middle contact of relay 1421, thence through 90 the frame connector 1500, conductor 220 to the grounded sleeve conductor of the busy horizontal link 206. Should the first and corresponding outgoing trunk 221 also be busy, a circuit is closed from battery, 95 through the left winding of relay 1420, inner back contact of relay 1421, thence through the trunk connector 1502, conductor 1528, to the grounded sleeve conductor of the busy trunk 221. Relay 1420 operates as a 100 result of either or both of its windings being energized. Similarly, if either the horizontal link 207 or the corresponding trunk 222 is busy, or both are busy, the next testing relay 1422 is operated.

Assuming, however, that the link 208 and trunk 217 are both idle at the time, the testing relay 1424 remains inert. The relay 1425 is now operated in a circuit from battery through the winding thereof, left back contact of relay 1424, left front contacts of relays 1422 and 1420 in series, conductor 1435, through the trunk connector 1502, and the distributing frame 1524 and returning through the trunk connector to conductor 1529, outer right contact of relay 1406, left back contact of slow relay 1402, to the grounded conductor 1020. Relay 1425 opens the operating circuits of relay 1424 to prevent an accidental operation of this relay. 115 120 125 130

The horizontal operating magnet 216 is now operated in a circuit from battery, through the right hand winding of said magnet, conductor 224, through the connector 1500, conductor 1530, to ground at the outer contact of relay 1425. Magnet 216 effects the connection through the district switch 200, thereby extending the trunk 102 to the selected idle outgoing trunk 217.

- 10 *Disconnection of the outgoing marker from the district frame and trunk group.*—The connection having been established, the outgoing marker may be disconnected by releasing the frame connector 1500 and the trunk connector 1502. First, however, a test is made which involves contact points on the district selector switch 400 to make sure that the same has properly operated before the marker releases. For this purpose, a circuit is closed from battery, through the winding of relay 1404, left back contact of relay 1405, thence through the inner front contact of relay 1425, conductor 1437, through the trunk connector 1502, conductor 1531, through contacts of the switch 200, sleeve conductor 124 of trunk 102 to ground. Relay 1404 locks and closes obvious circuits for operating relays 1402 and 1403. Relay 1403 at its right contact, opens the circuit of the vertical magnet 212, which releases. At its left contact, relay 1403 opens the holding circuits of the operated test relays in the marker, and also opens the holding circuits of vertical magnet 210 and multi-contact relay 1509.

Relay 1402 releases the relays 1511 and 1512, which in turn causes the release of relay 1513. Relay 1402 also releases relay 1425, which opens the operating circuit of magnet 216.

Relay 1402 also opens the circuit of relays 1504 and 1505, in turn causing the release of relay 1506.

Relay 1511 in releasing, releases the multi-contact relay 1516. Thus the outgoing marker has been disconnected from the district frame 200 by the release of frame connector 1500 and from the group of trunks by the release of the trunk connector 1502.

50 The connection through the district selector frame 200 is now held by the maintained operation of horizontal magnet 216 which is locked in a circuit from battery through both its windings in series, thence through contacts of the switch 200 to the grounded conductor 124.

55 *Sending class information from the outgoing marker to the sender.*—During the time the outgoing marker is connected to the sender, it transmits to said sender the necessary class information to enable the sender to proceed with the further control of the equipment in extending the call. This class information is obtained from the office code which is translated in the marker and

reproduced by the operation of the routing relays 1200. In the present instance, the call being of the local class, the class information to this effect is given the sender by virtue of the fact that the routing relay 1205 is 70 in operated condition.

Inasmuch as the incoming selectors 500 are divided into two groups, each group receiving one-half the trunks of a full group outgoing from the district frames 200, it 75 will be necessary later on to determine with which one of these groups the incoming marker should make connection. The routing relay 1205 identifies the particular group of incoming frames to which the selected trunk 217 leads. Therefore, this relay is in a position to give the sender an indication as to the group of incoming frames involved, and thereafter the sender can again transfer the indication to the incoming marker at the proper time. To accomplish this end, the class relay 822 in the sender is operated by means of a circuit which may be traced from battery through the winding of said relay, conductor 823, through the sender connector 900, conductor 1021, through the distributing frame 1213 to ground at the inner left contact of relay 1205. Relay 822 locks to the grounded conductor 819. 80 85 90 95

Release of the outgoing marker from the sender.—The outgoing marker may now be disconnected since it has completed its function in setting the district selector switch 200. When relay 1402 energizes, it causes the operation of relay 808 in the sender, by means of a circuit traceable from ground over conductor 1020, left front contact of relay 1402, contact of relay 1438, conductor 1439, back contact of relay 1450, conductor 1451, through the sender connector 900, conductor 918, winding of relay 808 to battery. Relay 808 locks to the grounded conductor 819. Relay 808 causes the release of relays 907 and 908. 100 105 110

Relay 907 releases relays 915 and 916, and also the multi-contact relays 901 and 906. Thus, the outgoing marker is disconnected from the sender and is available for use in connection with the same or another one of the senders. 115

When relay 808 operates, it also causes the release of the relay 1108, which in turn, causes the deenergization of the various energized relays in the marker. 120

Connection of the sender to the incoming marker.—The next step in the operation is to connect the sender through the sender-connector 1900 to an idle incoming marker for the purpose of controlling the selective operation of the incoming selector switch 500 and the connector switch 700 to complete the call. When relay 808 operates, it causes the operation of the relay 810. 125 130

The relay 810 causes the operation of re-

lay 1906 which is individual to the sender shown at the sender-connector 1900. The circuit for this purpose may be traced from ground, through the lower back contact of relay 1907, right contact of relay 1908, upper winding of relay 1906, conductor 1930, thence to conductor 1930, Fig. 8, to battery through a contact of relay 810.

It will be noted that several of the conductors leading from Fig. 8 have been bracketed and carried to Figs. 9 and 19 by the convention illustrated for the purpose of conserving space in the drawing.

Relay 1906 locks through its lower winding and the winding of relay 1907, causing the latter relay to operate. Relay 1906 operates the multi-contact relay 1901 and also initiates operation of controlling relays 1909, 1910, 1911, etc., of the connecting device in the manner explained in connection with the sender-connector shown in Fig. 19 to associate the sender with the first idle incoming marker. It will be assumed that the incoming marker shown in full is the first idle one and that the corresponding multi-contact 1905 shown in Fig. 19 is operated accordingly.

When a sender is connected to the marker, the marker start relay 2105 operates in a circuit traceable from ground through the winding of this relay, conductor 2110 through the sender-connector 1900 thence over conductor 1930 to battery at the contact of relay 810.

Transferring the numerical record from the sender to the incoming marker.—Now that the sender has been connected to the incoming marker the record of the thousands, hundreds, tens and units digits stored on the registers 801 in the sender is transferred and stored on the corresponding registers 2001, 2002, 2003 and 2004 in the marker.

The relays of the marker registers are operated and released in a manner similar to that described in connection with the corresponding registers of the outgoing marker.

For the number of the called line it may be assumed that relays 2005, 2009, 2010, 2015 and 2020 remain operated.

The indication recorded by the relay 822 in the sender, showing to which group of incoming selector frames the trunk 217 extends, is also transferred from the sender to the incoming marker. This transfer consists in operating relay 2313 by means of a circuit traceable from battery, through the winding of said relay, conductor 2318, through the sender-connector 1900, conductor 1932, thence to conductor 1932, Fig. 8 to ground at the right outer front contact of relay 822.

Connection of the incoming marker to the final translator.—The next thing to happen is the selection of a proper one of the trans-

lators which serves the group of called lines containing the line wanted for this call. This selection takes place by means of the numerical registers shown in Fig. 20. Since the relays 2009 and 2010 of the hundreds 70 register 2002 are operated, relay 2103 is operated in a circuit from battery, through the winding of said latter relay, thence over conductor 2112, middle right front contact of relay 2009, inner left front contact of relay 2010, outer right back contact of relay 2011, inner right contact of relay 2012, conductor 2022, contact of relay 2109, conductor 2113, left back contact of relay 2319, left back contact of relay 2320, right back contact of relay 2322, conductor 2323 to ground at the inner right front contact of relay 2105. Relays 2108 and 2109 operated as above explained in connection with corresponding relays of the outgoing marker. 85 With relay 2103 operated and register relay 2005 operated, a selecting circuit is completed for operating the relay 2202, individual to the incoming marker shown at the connecting device 2200 which reaches the 90 desired final translator. This circuit may be traced from battery, through the inner left contact of relay 2105, conductor 2114, left contact of relay 2322, conductor 2324, outer right contact of relay 2106, conductor 2115, 95 inner right contact of relay 2008, outer right back contact of relay 2007, left normal contact of relay 2006, outer right front contact of relay 2005, conductor 2023 lowermost contact of relay 2103, conductor 2116, right winding of relay 2202, back contact of relay 2203 to ground. Relay 2202 operates and locks through its left winding and the back contacts of relays 2207 and 2208 and the winding of the relay 2203 to ground. 100 Relay 2203 also operates to prevent interference by breaking the operating circuits of relays 2207, 2208, etc., individual to other numerical registers. With relays 2202 and 2203 operated, circuits are completed for operating the multicontact relays 2204, 2504, and 2509. These circuits may be traced from battery, through the windings of relays 2509, 2504 and 2204 in parallel through the outer right contact of relay 2202 to ground 115 at the front contact of relay 2203. The connecting relay 2204 extends the various leads from the incoming marker through to the final translator 2600.

Immediately that the marker is connected to the translator, relay 2615 is operated in a circuit from battery, through its winding, over the conductor 2611 through the connecting device 2200, conductor 2230, through contacts of register relays 2002 to ground 120 over conductor 2022 as above traced. Relay 2615 operates relay 2606 in a circuit from ground through the winding of relay 2606, conductor 2620, device 2200, conductor 2231 front contact of relay 2020, and thence over 125 130

conductor 2024 to battery at relay 2105 as above traced.

The apparatus is now in condition to select a vertical operating magnet on a final connector frame, which controls the vertical row of contacts in which appear the five called subscribers' lines containing the line wanted for this particular call. Therefore, the vertical magnet 713 is operated in a circuit traceable from battery, through the winding of said magnet, conductor 717, inner contact of relay 2606, conductor 2612, through the connector device 2200 conductor 2211, through the outer right front contact of relay 2015, inner right back contact of relay 2016, conductor 2025, outer right back contact of relay 2325, conductor 2321, conductor 2326, right back contact of relay 2322, thence to the grounded conductor 2323. Magnet 713 prepares the contacts in the vertical row 703 and also closes the circuit for operating the relay 2610. This circuit may be traced from ground through the contact of magnet 713, winding of relay 2610 to battery. The relay 2610 is individual to the connector frame 700 and serves to connect the horizontal operating and testing leads through to the incoming marker. Relay 2609 is individual to a second one of the final connectors of the same group and serves for a similar purpose.

Connection of the incoming marker to the incoming selector frame.—When the incoming marker is connected to the final translator, the connecting device 2200 causes the operation of relay 2315 which initiates the operation of the incoming frame connector 2400. The circuit for relay 2315 may be traced from battery, through the winding of said relay, conductor 2327, contacts of relays 2202 and 2203 to ground. Relay 2315 locks through its right contact to the grounded conductor 2323. Since the frame test relay 2313 is operated, indicating in which group of incoming frames the frame 500 occurs, a circuit is completed for relay 2402 of the frame connector 2400. Had the relay 2314 been operated, the frame connector 2401 would be employed to connect the marker to a second group of incoming frames. The circuit for relay 2402 may be traced from battery at the left inner armature of relay 2105, conductor 2114, left contact of relay 2322, left contact of relay 2315, contact of relay 2313, right winding of relay 2402 to ground at the contact of relay 2403. Relay 2402 operates and locks through its left winding, back contacts of other relays such as relay 2409, winding of relay 2403 to ground. Relay 2403 operates in this circuit and opens the operating circuits of the other relays similar to 2402, individual to other incoming markers. The multi-contact relay 2404 is

now operated in a circuit through the front contacts of relays 2402 and 2403.

The incoming frame connector 2400 when taken for use, completes a circuit for operating the vertical magnet 508 controlling the vertical row of contacts 502 on the incoming selector in which appears the trunk 217 over which the calling line has been extended. This circuit may be traced from ground through the front contacts of relays 2403 and 2402 thence over conductor 2410, left contact of relay 2317, conductor 2328, through the sender-connector 1900, conductor 1913, thence to conductor 1913, Fig. 8, thence over conductor 816, through the district selector switch 200, over the tip of trunk 217, through the upper front contact of relay 406, winding of relay 401 to battery. It will be noted that relay 406 is operated in a circuit from battery, through its winding and the back contact of relay 400 to ground on the sleeve conductor 325 of trunk 217. Relay 401 operates the vertical magnet 508, in an obvious circuit. Relay 401 also operates the multi-contact relay 2408 in an obvious circuit. With relays 2404 and 2408 operated, the leads from the incoming marker are extended through the frame connector 2400 to the incoming frame 500.

Magnet 508 of the incoming frame operates and prepares the contacts in the vertical row 502 and locks in a circuit through its winding and contact, thence through the frame connector 2400, conductor 2411, to the grounded conductor 2326. Multi-contact relay 2408 also locks in a circuit traceable through the frame connector 2400 to ground over conductor 2411.

The vertical magnet 512 which controls the row of contacts 506 in which appear the trunks of the group 524 leading to the proper group of idle connector switches, is now operated. The circuit for this magnet may be traced from battery, through the winding thereof, thence through the frame connector 2400, conductor 2412, contact of relay 2509 to ground on the grid wire. The magnet 512 is selected by the connecting device 2501 which constitutes a part of the final translator. The final translator being individual to the desired group of lines and consequently to the group of final connectors reaching these lines, selects the vertical magnet 512 as the one on the frame which controls the group of trunks reaching the said group of connector switches. The relay 2511 is individual to the subgroup 524 and this relay is operated in a circuit from battery through its winding, contact of relay 2509, thence through contacts of relays 2404 and 2408 to ground. The relays 2407, 2408, etc., have one of their contacts arbitrarily grounded in such a manner that when any one of these relays

relating to the incoming selectors on which a sub-group of trunks 524 in multiple is operated, the particular one of the relays 2511 2512, etc., which connects the marker 6 to the particular subgroup of trunks will also be operated.

Testing the horizontal links of the incoming and connector switches and the interconnecting trunks.—Inasmuch as the 10 testing operation concerns the final connector switch, it is necessary to associate the marker testing relays 2300 with the horizontal section 714 of the connector switch 700. This is accomplished 15 by operating the relay 2507 in a circuit from battery through the winding thereof, conductor 2530, through the device 2200, conductor 2213, inner back contact of relay 2017, back contact of relay 2018, back contact of relay 2019, conductor 2026, inner back contact of relay 2325, to the grounded conductor 2321. The relay 2507 is individual 20 to the section 714 in which the called line 716 appears, and therefore, this relay is the 25 one operated. Relays 2506, etc., are individual to other horizontal sections, representing other units digits in the connector switch 700.

The marker has now made all necessary 30 connections and is ready to test the incoming and final selector horizontal links and the trunks interconnecting these selector switches.

For the purposes of the call under consideration it will be assumed that the link 35 517 of the incoming switch, trunk 526 and link 708 of the connector switch are all simultaneously idle. Test relays 2301 and 2303 therefore remain deenergized.

40 At the time the vertical magnet 512 of the incoming selector operates, a circuit is closed from ground through the contact of this magnet, conductor 531, through the connector 2400, conductor 2413, windings of relays 45 2316 and 2317 in parallel to battery.

During the time the test is being made of the horizontal links and trunks, a test of the called subscriber's line is also taking place. When the final translator is connected to the connector switch 700 through 50 the connecting device 2601, the magnet 724 which controls the testing link 710 common to the connecting links of the section 714, is operated. The circuit for this purpose may 55 be traced from battery, through the right winding of said magnet, conductor 721, through the connecting device 2601, through the connecting device 2500, conductor 2326, to the grounded conductor 2321. Magnet 60 724 operates and prepares to test the condition of the called line 716 over the testing link 710. The test circuit extends from battery, through the left winding of test relay 2332, conductor 2333, through the connector 2501, through the connector 2601,

conductor 722, over the lower conductor of test link 710 to the sleeve conductor of the called line 716. Assuming the called line to be idle at this time, the test relay 2332 remains deenergized. The horizontal magnet 70 724 in operating, operates the relay 2334 in the marker, in a circuit traceable from battery, through the winding of said relay, conductor 2335, through the connectors 2001, and 2601, conductor 723, to ground at the 75 contact of magnet 724. With relays 2316 and 2334 operated, a circuit is closed for operating relay 2304. This circuit may be traced from battery, through the winding of said relay, left back contact of relay 2301, 80 conductor 2336, outer right contact of relay 2334, to ground at the inner contact of relay 2316. Relay 2304 operates the relay 2306 in an obvious circuit.

Relay 2304 identifies the idle trunk 85 526 whose idle condition has been ascertained and accordingly completes a circuit for operating the vertical magnet 711 in the connector switch which controls the vertical row of contacts 701 in which appears the 90 said trunk 526. The circuit for operating the magnet 711 may be traced from the grounded conductor 2321, outer left contact of relay 2304, conductor 2337, thence through the connecting devices 2501 and 95 2601, winding of magnet 711 to battery. Relay 2304 at its inner right contacts, opens the operating circuits of relay 2301 to prevent this relay from subsequently operating. Such other of the testing relays 2302, 100 etc., as are operated, at the time, lock in circuits leading through their left windings and locking contacts, thence over conductor 2338, inner right contact of relay 2334 to ground at the outer contact of relay 105 2316. By locking these relays, they are prevented from releasing in case the trunk or link becomes idle to disrupt the extended start circuit that leads through the successive contacts. 110

When the vertical magnet 711 of the connector switch energizes, it operates the relay 2339 in a circuit traceable from battery, through the winding of said relay, conductor 2340, thence through the connecting devices 2501 and 2601 to ground at the contact of magnet 711. Relay 2339 operates the horizontal magnet 521 of the incoming selector 500 and the horizontal magnet 720 of the connector switch 700. The circuit for magnet 521 may be traced from battery, through the right winding of said magnet, conductor 532, through the frame connector 2400, conductor 2414, outer right contact of relay 2304, conductor 2341, left contact of relay 2339 to the grounded conductor 2321. Magnet 521 operates, rotates the associated horizontal bar and extends the trunk 217 over link 517 to the idle trunk 526. The circuit for operating magnet 720 may be 130

- traced from battery, through the right winding thereof, conductor 728, through the connecting devices 2601 and 2500, conductor 2430, left contact of relay 2306, to the 5 grounded conductor 2341. Magnet 720 rotates the associated bar and effects connection from the trunk 526 through the horizontal link 708 to the called subscriber's line 716.
- 10 As soon as the connection is effected, the busy test relay 2332 is operated in a circuit through its left winding and thence over conductor 2333 as above traced to the lower conductor of the test horizontal link 710 to 15 the sleeve conductor of the called line, thence to the sleeve conductor of the horizontal link 708 through the left winding of magnet 720, thence over conductor 728 as above traced to ground. Relay 2332 operates and 20 locks through its right winding to the grounded conductor 2321. During this time, the release relay 2342 is also operated. The circuit for this relay may be traced from battery, through its winding, conductor 2343, inner right front contact of relay 2304, conductor 2344, through the connector device 2501, conductor 604, sleeve conductor 553 of the trunk 526, thence through contacts of switch 700 to ground over conductor 25 30 728 as previously traced.
- Release of the incoming marker and the translator.*—The connection having been completely established through the incoming and connector switches, the marker and translator may be discharged. With relays 2332 and 2342 operated jointly, relay 2346 is operated in a circuit from battery through the right winding of said relay, contact of relay 2342, outer front contact of relay 2332, 40 to the grounded conductor 2321. Relay 2346 locks through its left winding and contact to the grounded conductor 2323. Relay 2346 operates the relay 2322. This latter relay in operating, opens the holding circuits upon 45 which relays 2402, 2408, 2202, 2504, 2509, 2606 and 2315 depend. These relays release whereby the incoming marker is disconnected from the incoming frame and from the final translator and these mechanisms 50 are discharged. The holding circuits of the vertical operating magnets 508, 512, 711 and 713 are also open when the marker and translator are released. These magnets de-energize to restore the unused contacts in 55 their associated rows. The connection through the switches is held by the continued energization of the horizontal magnet over circuits which will be discussed hereinafter.
- 60 *Disconnection of the incoming marker from the register sender.*—The marker is also disconnected from the sender by releasing the sender connector 1900. To accomplish this, a notification is transmitted from 65 the marker to the sender informing it that disconnection should take place and the sender thereupon proceeds to release the sender-connector 1900 and the sender thereupon proceeds to release relays 1906 and 1907. These latter relays release and bring 70 about the release of the sender-connector 1900 whereby the sender is disconnected from the incoming marker.
- The release of the sender-connector 1900 releases relay 2105, the energized relays de- 75 pending upon this relay, together with the operated relays of the marker registers, and the translating device 2600 also release.
- The register sender, having completed its 80 functions may be released at this time together with the sender selector 106. Relay 107 is also released to extend the calling line 105 through to the repeating coil 109.
- Preparation for the application of ringing current to the called line.*—Referring back 85 to where the incoming selector 500 and the connector switch 700 are operated and the marker is released, a description will now be given of the manner in which these switches are held prior to describing the 90 preparation of the circuits for the application of ringing current to the called line.
- The horizontal magnet 521 of the incoming selector in operating, locks in a circuit from battery, through both its windings, 95 thence through contacts of the switch 500, to the sleeve conductor 426 of the trunk 217, winding of relay 400, to ground on the sleeve conductor 325. Magnet 521 holds and relay 400 operates in this circuit.
- 100 Relay 400 closes an obvious circuit for relay 408 which closes the trunk to the repeating coil 407.
- The relay 600 in the trunk circuit 526 also 105 operates over a path traceable from battery, through the winding of said relay, sleeve conductor 605, through contacts of the switch 500 to ground on the sleeve conductor 426. Relay 600 closes a holding circuit 110 for the horizontal magnet 720, traceable from battery, through both windings of said magnet, thence through contacts of the switch 700, conductor 533 to ground at the inner right front contact of relay 600. Relay 600 also operates the relay 602 in an 115 obvious circuit. Relay 602 which is slow to release affords a substitute path for applying ground potential to the sleeve conductor 533.
- 120 It may be noted that conductor 533 is grounded immediately that the switch 500 is operated to afford circuits for relays 2332 and 2242 in the marker which circuits are parallel to those previously traced.
- 125 Relay 400 releases the relay 406 which in turn releases relay 401. Ringing current may now be applied in any well known manner to signal the called station.
- 130 Following the application of ringing current relay 110 is operated and the conver-

sational connection is completed and conversation may now take place.

Release of the connection.—At the end of conversation the subscribers replace their receivers on the switchhooks causing the removal of ground potential from the holding conductor of trunk 102 and the consequent release of switches 100 and 200. Ground is also removed from conductors 325 and 426 causing the release of switch 500 and relay 600. Relay 602 subsequently releases removing ground from conductor 533 and permitting switch 700 to release.

Called subscriber's line tests busy.—It will be considered that the called subscriber's line 716 is already engaged at the time the marker makes a test thereof. This being the case, the ground potential exists on the sleeve conductor and the test relay 2332 operates in the circuit hereinbefore traced. Relay 2332 locks through its right winding and contact to the grounded conductor 2321. Since the relay 2339 has not operated at this time, relay 2332 causes the operation of relays 2320 and 2348. The circuit for this purpose may be traced from battery, through the windings of relays 2320 and 2348 in parallel, right contact of relay 2339, left front contact of relay 2332, to the grounded conductor 2321. Relay 2320 opens the circuit of relay 2103 which in turn brings about the release of the final translator from the incoming marker. In this manner, the connector switch 700 is disconnected from the incoming marker and the test relays in the marker which are operated, due to the busy condition of the horizontal links on the connector switch or trunks leading to the connector switch are released.

40 Relay 2320 operates the vertical magnet 510 on the incoming selector switch 500. The associated row of contacts is devoted to busy tone equipment for sending a busy tone back to the calling subscriber whenever the line is found to be engaged. The circuit for magnet 510 may be traced from battery, through the winding thereof, thence through the frame connector 2400, conductor 2416, inner right contact of relay 2320, the right back contact of relay 2322, to the grounded conductor 2323. It may be noted that the vertical magnet 512 is released at the time the translator is disconnected from the marker in order to prevent the busy tone apparatus from being connected to the trunks leading to the connector switches. Magnet 512 releases relays 2316 and 2317.

60 The magnet 510 in operating, completes a circuit traceable from ground through its contact, conductor 534, through the frame connector 2400, conductor 2417, right contact of relay 2317, thence through the inner contact of relay 2348, conductor 2336, left back contact of relay 2301, winding of relay 2304 to battery. Another circuit may be

traced through the outer right contact of relay 2348, thence over conductor 2341, through the outer right contact of relay 2304, conductor 2414, and thence as previously traced through the winding of horizontal magnet 521. Magnet 521 connects the busy tone device 535 to the trunk 217. Current flowing over the trunk through the right windings of repeating coil 407, induces a tone current in the left windings of the repeating coil which current flows through the calling subscriber's receiving set producing a characteristic sound therein, notifying him that the called line is busy.

The relay 2320 in operating, operates the relay 2550. Later, when ground is applied to conductor 2349, the relay 2351 operates, opening the circuit of relay 2350. Relay 2350 being slow to release, requires an interval to retract its armature. When relay 2350 releases, slow-to-operate relay 2352 operates in an obvious circuit and locks. After an interval, relay 2351 which is also slow-to-release, retracts its armatures. When relay 2351 releases, a circuit is closed from battery, through the right winding of release relay 2346, right contacts of relays 2351 and 2352 to ground. Relay 2346 brings about the release of the equipment in the manner described hereinbefore.

Establishment of an interoffice connection.

A description will next be given of the manner in which the equipment functions in establishing a connection from a calling subscriber's line in the local office over the district selector 200 and an office selector 300 to a trunk outgoing to a distant exchange.

Assume that the office code of the call is represented by the abbreviation letters ACA which in terms of dial impulses is represented by three series of two impulses each. Assume also that the number of the wanted line is the same as in the previous case, namely 2345. In this instance, the calling subscriber first dials three series of two impulses each, which are received in the sender as above explained and cause the operation of registers 800 and 801. The numerical impulses, when transmitted, cause the operation of the same numerical register relays as in the case of the call previously considered.

After the sender is associated with the outgoing marker, the office record is transferred and relays 1004, 1008 and 1012 of the marker registers are operated. By tracing the circuits through registers 1000 and 1001, it will be found that relays 1102 and 1105 of the translator 1100 are operated. With these relays operated, a circuit is completed for the routing relay 1208, and may be traced from battery through the winding of said relay, conductor 1217,

5 contact of relay 1102, contact of relay 1105, conductor 1119, middle right back contact of relay 1011, inner left front contact of relay 1012, outer right back contact of relay 1013, inner right contact of relay 1014 to the grounded conductor 1017.

When the district frame connector 1500 operates, it operates relay 1211 as above described. Relays 1211 and 1208 determine 10 the operation of relay 1206. The circuit for this purpose may be traced from ground through the outer left contact of relay 1208, winding of relay 1206, to battery at the contact of relay 1211. Relay 1206 operates 15 the trunk connector relay 1511 in the manner hereinbefore described. The circuit is now completed for the multi-contact relay 1515, which is individual to the group of trunks appearing in the row 205 of the 20 district switch, which lead to the office selectors, one of which is shown in Fig. 3. The circuit for this relay may be traced from battery, through the winding thereof, thence over conductor 1532, outer right contact of relay 1206, conductor 1215 to ground 25 through contacts of relays 1511 and 1512. Relay 1515 operates and the outgoing marker is thus associated with the group of trunks outgoing from the district to the 30 office selector switches.

The vertical operating magnet 213 is operated in a circuit from battery, through the winding thereof, through the frame conductor 1500, thence over conductor 1613, 35 through the middle right contact of relay 1206, conductor 1434 and thence to ground over the path previously traced at the contact of relay 1515. The magnet 213 prepares the contacts in the row 205 and 40 operates the relay 1406 as above explained.

The horizontal links in the district selector 200 and the outgoing trunks are tested simultaneously by means of the 45 marker testing relays. An idle pair of these is selected and the connection is established through the district selector switch in the manner fully explained hereinbefore. Assume, for example, the connection is extended through the district selector 200 to 50 the trunk 230 leading to the office selector switch 300 and appearing in the vertical row of contacts 302.

When the connection is effected through 55 the district selector, relay 1404 operates and in turn operates the release relays 1402 and 1403. Relay 1402 opens the circuit of relay 1504 causing the release of the district frame connector 1500. This relay 1402 also releases the relay 1511 causing the release 60 of the district trunk connector 1502. Thus, the outgoing marker is disconnected from the district frame 200 and the trunks outgoing therefrom. It will be recalled that relay 1402 on the previous call sent a signal

back to the sender notifying the sender that it should release from the marker. Inasmuch as the office switch must be operated in this case, this signal is prevented by the operation of relay 1438 as will be presently described. Relay 1402 is slow to operate 70 to give relay 1438 sufficient time to energize.

The trunks leading from the district to the office frames may be arranged in two or more subgroups in case the total group is larger than a single vertical row of contacts can accommodate. In order to distinguish the particular subgroup involved, all the trunks of a given subgroup are identified by the characteristic circuit connected to the contact of relay 320, there being one 80 of these for each trunk in the subgroup. In the present case, a low resistance 321 is connected to the back contact. For a second subgroup, the resistance 321 would be high. Immediately that the connection is 85 established through the district selector frame 200, a circuit is closed through the windings of relays 1440 and 1441. This circuit may be traced from ground, through the low resistance 321, inner back contact of 90 relay 320, thence over the ring side of trunk 230, through the district selector switch 200, conductor 121, through the sender selector switch 106, conductor 821, through the sender-connector 900, conductor 1022, outermost 95 back contact of relay 1401, windings of relays 1440 and 1441 to battery. Since the resistance 321 is low, both the marginal relay 1440 and the relay 1441 operate. These relays lock to the grounded conductor 1020. 100 Relay 1441 operates relay 1442, which also locks.

At the time relay 1206 operated, it caused the operation of relay 1443, in a circuit from battery through the winding of the latter relay, thence over the conductor 1444, to ground at the contact of relay 1206. Relay 1443 locks to the grounded conductor 1020. Relay 1438 is now operated in a circuit from battery, through its winding, outer left contact of relay 1443, conductor 1115, left back contact of relay 1109 to ground at the contact of relay 1108. Relay 1438 thus prevents the sender from receiving a notification to release from the district marker until 115 after the office selector switch has been operated.

Connection of the outgoing marker to the office selector frame.—As soon as relay 1443 operates, it causes the operation of the relay 120 1602, individual to the marker in the office frame connector 1600. The circuit for this purpose may be traced from ground, through the back contact of relay 1603, right winding of relay 1602, conductor 1614, right 125 contact of relay 1443, right front contact of relay 1440, left contact of relay 1442, right contact of relay 1407, to battery over con-

ductor 1118. Relay 1602 locks in series with relay 1603 and the two jointly cause the operation of multi-contact relay 1604.

The vertical magnet 309 of the office selector switch 300 is operated due to the operation of the frame connector 1600. The circuit for operating this magnet may be traced from battery, through the winding thereof, conductor 312, outer back contact of relay 10 320, thence over the tip of the trunk through the district selector switch and thence over conductor 816 as previously traced, sender-connector 900 thence through the inner left front contact of relay 1406, inner left contact of relay 1401, conductor 1446, contacts of relays 1602 and 1603 to ground. Relay 1412 is also operated in parallel with the circuit above traced. The magnet 309 prepares the contacts of the vertical row 15 302 and also operates the multi-contact relay 1606 which is individual to the particular office selector frame 300. The circuit for this latter relay may be traced from battery, through the winding thereof, thence through 20 the contact of magnet 309 to ground on conductor 312. The magnet 309 and relay 1606 lock in circuits, through their windings thence over a path through the office frame connector 1600, conductor 1615, through the 25 left contact of relay 1408, left front contact of relay 1402, to the grounded conductor 1020.

Connection of the outgoing marker to the trunk group at the office selector switch.—
35 The relay 1412 which operates when the frame connector 1600 operates, closes an energizing circuit for the relay 1607 of the office trunk connector 1601. This circuit may be traced from ground, through the back contact of relay 1608, right winding of relay 1607, conductor 1616, thence through the inner right contact of relay 1208, conductor 1221, contact of relay 1412 40 through the right contact of relay 1407, to battery over conductor 1418. Relay 1607 operates and locks through its left winding and the winding of relay 1608 and the latter relay also energizes. Relays 1607 and 1608 jointly operate the multi-contact relay 50 1609.

Assume that the group of trunks leading to the desired office appear in the vertical row 304 of the office selector switch 300, and that the relay 1617 is individual to this 55 particular group. Relay 1617 accordingly is operated in a circuit traceable from battery, through the winding thereof, conductor 1618, through the outer right contact of relay 1208, conductor 1222, through contacts 60 of relays 1607 and 1608 to ground. Relay 1617 operates the relay 1610, whereby the test conductors of the trunks in the outgoing group are connected through to the test relays 1400 in the marker.

65 The vertical operating magnet 311 is next

energized by means of a circuit from battery, through its winding, thence over conductor 313, through the frame connector 1600, conductor 1619, through the middle right contact of relay 1208, thence over 70 conductor 1223, through the right contact of relay 1408, conductor 1447, through contacts of the trunk connector 1601 to ground. It will be noted that relay 1405 operated in parallel with the circuit just traced. The magnet 311 prepares the contacts in the vertical row 304 and also operates the relay 1401 in a circuit traceable from battery, through the winding of said relay, conductor 1448, through the frame connector 1600, 80 to ground at the contact of magnet 311.

Testing the horizontal links of the office switch and the outgoing trunks.—The horizontal links 305, 306, 307, 308, etc., of the office switch 300, and the corresponding trunks of the outgoing group are tested by means of the test relays 1400 in the marker in exactly the same manner as discussed in connection with the district selector 200. Assume that the link 308 and the corresponding trunk 314 are both idle, and that no preceding trunk and its corresponding link are both idle. Accordingly, relays 1420, 1422, 1424 are all operated and relay 1426 is the first one in the series to remain deenergized. The relay 1427 is next operated in a circuit from battery, through its winding, left back contact of relay 1426, left front contacts of the preceding test relays 90 thence over conductor 1435, thence through the office trunk connector 1601, through the inner left contact of relay 1617, and returning through a contact of the office connector over conductor 1630, outer right contact of relay 1401, left contact of relay 1407, left front contact of relay 1402 to ground on conductor 1020. Relay 1427 at its outer right contact, closes a circuit through the frame connector 1600 for the horizontal magnet 315. The magnet 315 locks through its windings and contacts of the switch 300, thence over conductor 331, through the relay 320 and the district selector switch 200 to ground on the sleeve conductor 124 of the trunk 102. Relay 320 operates and completes the tip and ring conductors of the trunk and opens the operating circuit of the vertical magnet 309.

Release of the marker from the office selector switch.—The connection through the office switch has thus been established and the marker may now be released. This is accomplished by operating relay 1460 in a circuit from battery, through the winding thereof, left front contact of relay 1405, conductor 1461, inner right contact of relay 1427, conductor 1452, through the trunk connector 1601, conductor 330, through contacts of the switch 300, to ground on conductor 331. This circuit provides a test to 120

- ascertain whether the office frame has completed the connection. Relay 1460 locks through its right front contact and operates the relays 1407 and 1408. These relays bring about the release of the office frame connector 1600 and the office trunk connector 1601, whereby the marker is disconnected from the office switch. Relay 1407 operates the relay 808 in the sender notifying the sender that the connection has been completed and that the time is ready for releasing. This circuit may be traced from ground, over conductor 1020, through the left front contact of relay 1402, left front contact of relay 1407, thence over conductor 1439, as previously traced through the winding of relay 808 to battery. The sender thereupon brings about the release of the sender-connector 900 and the outgoing marker is disassociated from the sender and restored to common use.

The vertical magnets 309 and 311 of the office switch are released and the connection therethrough is maintained by the continued energization of the horizontal magnet 315.

Release of the connection may take place as above described.

An outgoing marker encounters trouble.

- In the establishment of the connections hereinbefore described, both the outgoing marker and the incoming marker functioned normally and therefore completed their control over the associated mechanism within the predetermined intervals of time allotted for this purpose. The markers may, however, become disabled at any of the various points in their progress from the time they are seized until they have completed the exercise of their control over the associated switches and other apparatus. In order to illustrate the manner in which the trouble indicator, shown in Fig. 18, operates, it will next be assumed that the outgoing marker encounters trouble at any one of several of its different stages of operation. For this purpose it may be assumed that the connection being established is one which requires the use of both a district and an office selector switch.

At the instant the outgoing marker is seized by a sender through the sender connector, relay 1108 operates as explained. This relay initiates the operation of the time measuring device shown in Fig. 13 which counts an interval of time sufficient for the marker, if functioning normally, to control the district and office selector switches 200 and 300 and to release in the regular manner. The time measuring device includes a series of counting relays 1300 which operate successively under the control of the constantly driven interrupter 1309. These relays apply ground potential at regular intervals of time to the various conductors

leading to the distributing frame 1307. By strapping the conductor 1319 to various ones of these conductors, the time interval measured may be adjusted as desired.

As soon following the operation of relay 1108 as the interrupter 1309 closes, relay 1302 is operated in a circuit from ground, through the interrupter 1309, conductor 1320, outer left contact of relay 1108, conductor 1120, right contact of relay 1308, conductor 1321, right contact of relay 1301, winding of relay 1302 to battery. Relay 1302 operates and prepares a circuit from battery, through its winding, left winding of relay 1301, contact of relay 1302, back contact of relay 1304, back contact of relay 1306, conductor 1322, thence over conductor 1020 to ground. Relay 1301, however, being shunted does not operate. When the interrupter 1309 opens its contacts, the shunt is removed and relay 1301 operates in series with relay 1302. On the next closure of the interrupter, grounded conductor 1321 is extended through the right front contact of relay 1301, right back contact of relay 1303, winding of relay 1304 to battery. Relay 1304 operates and opens the circuit for relay 1302 traced through the left winding of relay 1301. Relay 1301 locks through its right winding, but relay 1302 releases. Relay 1304 prepares a locking circuit through its own winding and the left winding of relay 1303, front contact of relay 1304, thence to the grounded conductor 1322 as traced. On the next opening of the interrupter, relay 1301 releases and the shunt being removed relay 1303 operates in series with relay 1304.

On the next closure of the interrupter, grounded conductor 1321 is again extended to the winding of relay 1302. This relay operates and prepares a circuit for relay 1301 which operates the next time the interrupter opens. On the next closure of the interrupter the grounded conductor 1321 is extended through the right front contacts of relays 1301 and 1303 and the right back contact of relay 1305 to the winding of relay 1306. The operation of relay 1306 opens the holding circuit of relays 1302 and 1304 which release. Following this, the interrupter opens and releases relays 1301 and 1303 and permits relay 1305 to operate in series with relay 1306. Thus, the counting relays are operated in different combinations under the control of the interrupter 1309. From inspection it will be found that ground potential is placed on the various conductors leading to the distributor frame 1307 at succeeding intervals of time. With the distributing frame cross connected as illustrated, relay 1308 is operated as soon as the counting relays 1300 have functioned until both relays 1301, 1303 and 1305 are operated simultaneously. The circuit for relay 1308 may be traced from battery, through

its winding, distributing frame 1307, middle front contact of relays 1301, 1303 and 1305 to the grounded conductor 1322.

If the marker encounters trouble immediately that the relay 1108 operates, the interval of time is counted and relay 1308 becomes energized. Relay 1308 operates relay 1311 in a circuit from battery, through the winding of relay 1311, inner right contact of relay 1310, right normal contact of slow release relay 1314, conductor 1323, left contact of relay 1308 to grounded conductor 1322. Relay 1311 operates the slow release relay 1312 which in turn operates the slow release relay 1313 which thereby operates the slow release relay 1314.

When relay 1313 operates, it initiates the operation of the connecting device 1700 for the purpose of connecting the trouble indicator to the particular marker that is in trouble. To this end, relay 1703 individual to the marker is operated in a circuit from battery, through the right front contact of relay 1313, right contact of relay 1315, key 1324, conductor 1325, upper winding of relay 1703, right contact of relay 1705, lower contact of relay 1704, conductor 1706, to ground through key 1840. Relay 1703 locks through its lower winding and front contact, and the winding of relay 1704 to ground. Relay 1704 operates and causes the operation of multi-contact relay 1701 in a circuit traceable from battery, through the winding of relay 1701, upper contact of relay 1703 to ground at the inner contact of relay 1704. Relay 1701 operates and connects the various leads from the trouble indicator shown in Fig. 18 through to the marker.

When relay 1314 operates, it opens the circuit of relay 1311, which relay releases, in turn releasing relay 1312 which in turn releases relay 1313, thereby releasing relay 1314. Relays 1312, 1313 and 1314 being slow to release provide an appreciable interval of time for the apparatus to function. As soon as relay 1313 releases, it removes battery from conductor 1325, causing the release of relays 1703 and 1704 and consequently the release of relay 1701 and the disconnection of the trouble indicator from the marker.

Upon the release of relay 1313 and while relay 1314 is still operated relay 1310 is operated in a circuit from battery, through its winding, left contacts of relays 1314 and 1313 to ground. Relay 1310 immediately locks through its inner left contacts, left contact of relay 1308 to conductor 1322. Relay 1310 opens the circuit of relay 1311 to prevent a repetition of the circuit. Relay 1310 at its outer left contact closes a circuit through relay 1317 and the magnet 1316 of the peg count register. Magnet 1316 operates the register to record the occurrence of the trouble.

Relay 1310 also operates relay 1450 in the marker. Relay 1450 closes obvious circuits for relays 1404 and 1460. In case the marker had progressed to a point where it was associated either with the district or office switches, the operation of relays 1404 and 1460 would bring about a release in the manner hereinbefore explained. Relay 1450 also applies ground potential to conductor 1440 which extends back into the sender to notify the sender that it may release and also cause the release of the sender connector and the marker. The release of the marker causes the release of the operating relays of the time measuring device.

During the time the trouble indicator is associated with the marker, certain of the relays, 1801 to 1836 inclusive, are operated to record certain information regarding the apparatus involved and the amount of progress which has been made up to the point where the trouble occurred. Relay 1801 is operated in a circuit from battery through its winding, conductor 1841, contact of multi-contact relay 901, contact of relay 906, conductor 922, contact of relay 1701 to ground. Since relay 901 is individual to the particular sender illustrated, relay 1801 in the indicator by operating, records the fact that this particular sender is the one involved in the present connection. Had another sender, such as the sender represented by the multi-contact relay 903, been the one concerned, relay 1802 in the indicator would have been operated. Relay 1801 immediately locks through its right contact, over conductor 1842 to ground through key 1840.

Relay 1812 is operated in a circuit from battery, through its left winding, thence to contacts of relay 1701 to ground. Since relay 1701 is individual to the particular marker which has encountered trouble, the operation of relay 1812 records the identity of this particular marker. Had another marker been involved, such as the marker represented by relay 1702, then relay 1811 would have operated. Relay 1812 locks to the conductor 1842.

It will be recalled that immediately the marker is connected to the sender, the record of the office code is transferred from the office register to the registers 1000, 1001 and 1002. If this record is represented by the operative condition of relays 1004, 1008 and 1012, a similar record is established on relays in the trouble indicator. Relay 1820 which corresponds to relay 1004, operates in a circuit from battery, through the winding of relay 1820, conductor 1843, through the connector 1700, conductor 1707, thence to ground in parallel with the operating circuit of relay 1004. Relay 1826 which corresponds to relay 1008 is operated in a circuit from battery, through the winding of

relay 1826, conductor 1844, through connector 1700 to ground in parallel over the operating circuit of relay 1008. Similarly, relay 1832 which corresponds to relay 1012 is operated. These relays lock to the grounded conductor 1842.

Since the marker has not progressed farther than these operations, no further record is taken by the trouble indicator. The 10 operated relays of the trouble indicator remain locked after the indicator is released from the marker and cause the illumination of corresponding lamps. Relay 1801 at its left contact completes an obvious circuit for the illumination of lamp 1846. Similarly, relays 1812, 1820, 1826 and 1832 complete circuits for lamps 1847, 1848, 1849 and 1850. Lamp 1846 identifies the sender and lamp 1847 identifies the marker. 15 Lamps 1848, 1849 and 1850 illuminate to show the office code that the subscriber has dialed to the sender. The fact that no other lamps are illuminated shows the stage to which the marker has progressed at the 20 time trouble occurs.

If the register relays 1000, 1001 and 1002 in the marker operate properly upon the transfer of the record, the series circuit is completed for operating relay 1110 as described. If relay 1110 has operated before trouble occurs an indication of the fact that it has operated will be given by the trouble indicator. For this purpose, relay 1818 is operated in a circuit from battery through 30 its winding, conductor 1851, through connector 1700, conductor 1710 to ground through the series contact of the register relays 1000, 1001 and 1002. Relay 1818 locks and closes a circuit for illuminating 35 lamp 1852.

If the marker proceeds to the point where the district frame connector 1500 has operated before the trouble occurs, an indication of this fact is given to identify the particular district frame concerned in addition to the other information previously described. Since the frame connector 1500 is in operative condition at the time the trouble indicator is associated, relay 1803 is operated 45 in circuit from battery, through its winding, conductor 1853, through contacts of relay 1509, contacts of relay 1507, conductor 1533 through the connector 1700 to ground. Relay 1803 locks and closes an illuminating circuit for lamp 1854. It will be noted that relay 1803 is individual to relay 1509 which in turn is individual to the particular district frame 200 shown. Hence, the illumination of lamp 1854 shows that 50 the district frame 200 is the one through which the connection is being extended. Had another district frame been involved, such as the one to which relay 1508 relates, then relay 1804 in the trouble indicator

would have operated to illuminate lamp 65 1855.

If trouble does not occur until the district trunk connector 1502 has operated, the trouble indicator, in addition to indicating the sender, marker, the record dialed and other information above related, also shows the fact that the trunk connector has operated before trouble occurs. For this purpose, relay 1829 is operated in a circuit from battery, through the winding of said relay, 75 conductor 1856, through connector 1700, conductor 1711, conductor 1525 through the trunk connector 1502 to ground. Relay 1829 locks and closes a circuit for lighting lamp 1857. Had another trunk connector 1503 been involved, then another relay similar to relay 1829 would have operated in the trouble indicator to identify such other connector.

Provided the trouble does not occur until after the circuit for the district trunk vertical magnet 213 has been closed, the trouble indicator will provide a record of this fact. To this end, relay 1814 is operated in a circuit from battery through its winding, conductor 1860, through connector 1700, conductor 1713, thence to ground over conductor 1613 in parallel with the operating circuit for the vertical magnet 213, as previously traced. Relay 1814 closes an illuminating circuit for lamp 1861 which identifies the particular trunk vertical magnet 213 which the marker is attempting to operate. Had the trunk vertical magnet 212 been involved, then relay 1813 would have 100 been operated in the trouble indicator.

If the district trunk vertical magnet 213 is successfully operated before the trouble occurs, this fact is indicated by operating relay 1823. The circuit for this relay may be traced from battery, through its winding, conductor 1858, through connector 1700, conductor 1714, thence over conductor 1527 through the frame connector 1500 to ground at the contact of the operated vertical magnet 213. Relay 1823 causes the illumination of lamp 1859.

Should the operation progress to the point where the horizontal link is selected in the district frame before the trouble indicator is associated, an indication is given to show the particular link concerned in addition to the other information above explained. For this purpose, relay 1809 is operated in a circuit from battery through its winding, conductor 1862, through connector 1700, conductor 1715, left back contact of relay 1424, left front contact of relays 1422 and 1420 and thence to ground over conductor 1425 as previously traced. Relay 1809 locks and causes the illumination of lamp 1863 to indicate that the horizontal link 208 of the district selector switch 200 is the one which

has been selected for use in extending the connection through the switch. Had some other horizontal link been involved, then another of the relays 1807, 1808, etc., would 5 have been operated.

Should the trouble not occur until after the connection has been established through the district switch and the release relay 1404 has operated, the trouble indicator will give 10 an indication of this fact. Accordingly, relay 1835 is energized in a circuit from battery, through its winding, conductor 1864, through connector 1700, conductor 1716, left back contact of relay 1405 to ground over 15 conductor 1461 as previously traced. Relay 1835 locks and closes a circuit for lamp 1865.

It will be recalled that following the operation of the district switch, the office frame connector 1600 is operated to associate 20 the marker with the office switch 300. If the operation progresses to this point before trouble arises, the office frame relay 1805 is operated in the trouble indicator. The circuit for this relay leads from battery, through its winding, conductor 1866, 25 through contacts of the relay 1606, contacts of relay 1604, conductor 1620, to ground through contacts of the connector 1700. Relay 1805 causes the illumination of lamp 30 1867 which indicates that the particular office frame 300 is the one through which the marker is attempting to establish the connection. Had some other office frame been involved, then the corresponding relay as 35 1806 would have operated.

Provided the office trunk connector 1601 is operated before the indicator is associated, relay 1830 is operated in a circuit from battery, through its winding, conductor 1868, 40 connector 1700, conductor 1718, conductor 1447, through contacts of connector 1601 to ground. Relay 1830 locks and causes the illumination of lamp 1869.

If the office trunk vertical magnet 311 has 45 had its circuit closed, relay 1816 is operated in a circuit from battery, through the winding of said relay, conductor 1870, connector 1700, conductor 1719 thence to ground over conductor 1619 as previously traced. 50 Relay 1816 closes a circuit for illuminating lamp 1861. Lamp 1861 together with the other lamps which are illuminated at this time, indicates that a circuit has been closed for the office trunk vertical magnet 311. If 55 the office trunk vertical magnet succeeds in operating before the indicator is associated then relay 1824 is energized in a circuit from battery, through the winding of said relay, conductor 1871, connector 1700, conductor 60 1720 thence over conductor 1448, through the frame connector 1600 to ground at the contact of magnet 311. Relay 1830 causes the illumination of lamp 1869.

If the connection has progressed to the

point where a horizontal link in the office 65 selector switch 300 has been selected, one of the relays 1807, 1808, 1809, etc., is operated, indicating the particular horizontal link involved. In the case assumed, relay 1810 is energized in a circuit from battery, through 70 its winding, conductor 1873, connector 1700, conductor 1721, left back contact of relay 1426, left front contacts of relays 1424, 1422 and 1420 and thence over conductor 1435 to ground as previously traced. Relay 1810 75 operates and locks and closes a circuit for lamp 1874.

It may happen that the complete connection is extended through the district and office switches and the release relay 1460 80 operated before the marker encounters trouble which prevents it from releasing in the normal manner. Accordingly the trouble indicator is associated and, in addition to all the previous information described, relay 1836 is operated to show that the marker release relay 1460 is operated. The circuit for relay 1846 leads from battery, through the winding thereof, conductor 1875, connector 1700, conductor 1721, front contact 85 of relay 1405 and thence to ground over conductor 1461 as above traced. Relay 1836 closes an illuminating circuit for lamp 1876.

Thus, it will be seen that the trouble indicator shown in Fig. 18 may be associated 90 with any one of the several markers in response to the time measuring device associated with the marker provided such marker has encountered trouble at any of the various stages of its operation. Dependent upon the particular point at which the trouble occurs, the indicator will give 100 various signs of information which are of assistance in determining the nature of the trouble and in locating the exact point in the system where it occurs. While only the more important items have been taken into account in the disclosure, it will be obvious 105 that the trouble indicator may be extended to secure an indication of various other 110 operative conditions in the marker in order to enable the tracing of the trouble more minutely to the exact points of its occurrence.

Inasmuch as the trouble indicator is common to all of the outgoing markers it may 115 happen that, at the time the particular marker finds trouble and attempts to appropriate the indicator, the said indicator is already engaged in connection with another 120 marker. The circuits are so arranged that double connection of the indicator to the markers is prohibited. At the time the indicator is connected to the marker as above related, relay 1705 associated with connector 1700 is energized in a circuit closed through contacts of the connecting device 1700. Relay 1705 at its right contact opens the cir- 125

cuits of all relays similar to relay 1703, thereby preventing the connector from being taken for use a second time.

If another marker encounters trouble and its time measuring device measures off the prescribed interval, relay 1311 of such device is operated as hereinbefore explained. At this time, relay 1315 is operated in a circuit from battery, through the left contact of relay 1311, right winding of relay 1315, conductor 1327 to ground at the left contact of relay 1705. Relay 1315 operates and locks through its right winding and contact to grounded conductor 1322. Relay 1315 at its right armature opens the starting circuit and thereby prevents the marker from attempting to seize the trouble indicator while it is already engaged.

20 *An incoming marker encounters trouble.*

It will next be assumed that a local connection is being established in the manner hereinbefore described in detail involving one of the incoming markers shown in Figs. 20, 21 and 23. Common to all of the incoming markers, there is provided a second trouble indicator shown in Fig. 28 together with a connecting device 2700 for associating the indicator with any one of the incoming markers which encounters trouble. For initiating the operation of the connector 2700 each marker is provided with a time measuring device shown in the lower part of Fig. 24. This device is substantially the same as the one shown in Fig. 13 for the outgoing marker.

First the time counting device will be explained and then the various trouble conditions which may arise in the incoming marker will be assumed for the purpose of describing the trouble indicator. At the time the marker is seized, relay 2105 is operated and as soon thereafter as the interrupter 2428 closes, ground potential is applied to the conductor 2443 over the following path: ground, through the contact of interrupter 2448, conductor 2444, outer left contact of relay 2105, conductor 2118, left contact of relay 2429 to conductor 2443. In the manner described in detail in connection with the time measuring device of the outgoing marker, the counting relays 2420 operate in response to the successive application and removal of ground potential from conductor 2443. After an interval has been counted, relay 2429 is operated in a circuit from battery, through its winding, distributing frame 2447, middle left contacts of relays 2421, 2423 and 2425, conductor 2445, ground over conductor 2323. Relay 2421 opens the counting circuit and closes a circuit for relay 2432. This latter circuit may be traced from battery, through the winding of relay 2432, outer right contact of relay 2435, left normal contact of slow release

relay 2437, right contact of relay 2429 to grounded conductor 2445. Relay 2432 closes an obvious circuit for the slow release relay 2433 which in turn closes a circuit for slow release relay 2434 thereby closing a circuit 70 for slow release relay 2437. Relay 2437 opens the circuit of relay 2432 and the relays release in the same order of their energization. When relay 2434 operates it closes an operating circuit for relay 2703 traceable 75 from battery, through the right contact of relay 2434, right contact of relay 2436, key 2446, conductor 2447, upper winding of relay 2703, right contact of relay 2704, lower contact of relay 2704 to ground through the 80 contact of key 2843. Relay 2703 locks in series with the winding of relay 2704 and these two relays jointly complete a circuit for relay 2701 thus associating the trouble indicator with the marker. 85

Following the release of relay 2434, relay 2435 is operated in a circuit from battery, through the winding of the latter relay, right contact of relay 2437 to ground at the left contact of relay 2434. Relay 2435 locks 90 to conductor 2445 and also operates the peg count register 2442. Relay 2435 at its outer left contact operates relay 2431. Relay 2431 at its left contact closes a circuit for operating the marker release relay 2346. This relay serves to bring about a release of the marker as hereinbefore explained. When relay 2434 releases it opens the circuit of relays 2703 and 2704 and the trouble indicator is disassociated from the marker. 95

If the trouble occurs immediately that the marker is attached to the sender, certain lamps are illuminated identifying the sender involved, the marker and also the numerical record which the subscriber has caused to 105 be recorded. To this end, relay 2802 is operated in a circuit traceable from battery, through the winding of said relay, conductor 2844, thence through a contact of relay 1901, conductor 1923, through the connector 110 2700 to ground. Relay 2802 operates and locks over conductor 2846 to ground through the contact of key 2843. Relay 2802 closes a circuit for lighting lamp 2845 which identifies the particular register sender that has 115 been connected to the incoming marker.

The marker identifying relay 2812 is operated in a circuit from battery, through its winding, thence through the contact of relay 2701 to ground. Since relay 2701 is individual to the particular incoming marker taken for use, relay 2812 which is also individual thereto, closes a circuit for lamp 2847 to identify this particular marker. Another relay 2811 is shown which relates to 120 another of the incoming markers. 125

For the call hereinbefore considered, it was assumed that the numerical record was such that register relays 2005, 2009, 2010, 2015 and 2020 were operated. A record of 130

- this registration is taken on the trouble indicator. Relay 2819 operates in a circuit from battery through its left winding thence through connector 2700, over conductor 2710 to ground in parallel with a circuit for register relay 2005. In a similar manner relays 2825, 2826, 2832 and 2839, corresponding respectively to relays 2009, 2010, 2015 and 2020 are operated and locked to the conductor 2806. These relays close illuminating circuits for lamps 2848, 2849, 2850, 2851 and 2852 which indicate the numerical designation that the calling subscriber has dialed.
- If relay 2106 in the marker has operated before the trouble occurs, this fact is indicated by the operation of relay 2829 in the trouble indicator. The circuit may be traced from battery, through the left winding of the latter relay, conductor 2853, connector 2700, conductor 2711, inner left contact of relay 2106 to ground at the outer right contact of relay 2105. Relay 2829 closes an illuminating circuit for lamp 2854.
- If the marker has attached itself to a final translator and to one of the final frames 700, this fact is recorded by operating one of a number of relays 2809, 2810, etc. These relays are each individual to a final frame in the group, relay 2809, for example, being individual to frame 700 illustrated. The circuit for relay 2809 may be traced from battery, through its winding, conductor 2855, through contacts of the relay 2610, conductor 2617, through the connector 2200, conductor 2233, through connector 2700 to ground. Since relay 2610 is individual to frame 700, relay 2809 in operating illuminates lamp 2856 to identify the particular frame 700 as the one through which the connection is being established.
- Should the called line occur in the horizontal section 714 of connector switch 700 and the trouble not arise until after the connecting device 2500 has fully operated then one of a number of relays, 2840, 2841, etc., is operated to identify this particular horizontal section. Relay 2841 being individual to section 714 is operated in circuit from battery, through its left winding, conductor 2857, connector 700, conductor 2715, thence to ground through contacts of the register relays 2004 as previously traced. Relay 2841 causes lamp 2858 to be illuminated.
- Provided the circuit for relay 2315 is being closed at the time the trouble indicator is associated, relay 2834 is operated in a circuit through the left winding of said relay, conductor 2859, connector 2700, conductor 2327, and thence to ground as above traced in parallel with the operating circuit of relay 2315. Relay 2834 causes lamp 2860 to be illuminated.
- If the incoming frame connector 2400 has just operated at the time the indicator is

associated, one of the relays 2803, 2804, 2805, 2806, etc., is operated. In this instance, relay 2806 is energized in a circuit from battery, through its winding, conductor 2861, contacts of relay 2408, contacts of relay 2404, conductor 2449 to ground through connector 2700. Relay 2806 closes a circuit for lighting lamp 2862. This lamp identifies the incoming frame 500 as the one involved in the connection.

Should the trouble indicator be associated at the time vertical magnet 512 on the incoming switch is being operated, or after the same has been operated, relay 2817 is energized in a circuit from battery, through its winding, conductor 2863, connector 2700, conductor 2717, thence to ground over conductor 2413 as previously traced. Relay 2817 locks and causes the illumination of lamp 2864.

If the vertical magnet 711 on the final connector frame 700 is operated, relay 2823 is energized in a circuit from battery, through its left winding, conductor 2865, connector 2700, conductor 2718, thence to ground over conductor 2340 in the manner hereinbefore described. Relay 2823 causes the illumination of lamp 2866.

Should the horizontal link on the incoming switch have been selected at the time the trouble indicator is associated, one of the identifying relays 2807, 2808, etc., is operated in the indicator. Since the link 517 is utilized, relay 2807 is operated in circuit from battery, through its winding, thence through connector 2700, conductor 2719, left back contact of relay 2301 to ground over conductor 2336 as traced. Relay 2807 causes the illumination of lamp 2867 to identify the horizontal link 517.

Provided the released relay 2346 is operated, the relay 2835 in the indicator is energized in a circuit from battery through its winding, conductor 2868, through the connector 2700, conductor 2720, left contact of relay 2346, to ground over conductor 2323. Relay 2835 causes the illumination of lamp 2869.

Thus, the trouble indicator may be associated with any incoming marker at any stage of its operation when such marker encounters trouble, and sets a visual indication on the various lamps, showing the association of the marker with the various pieces of apparatus and the marker progress that has been had at the time the indicator is associated. From this information, the attendant can readily locate the source of the trouble.

From the foregoing description, it will be seen that the trouble indicators are always ready to serve in connection with every call that is handled by the switching apparatus. They are only brought into use as seen in the event that one of the markers finds

trouble for one reason or another and the time measuring device counts off the prescribed interval of time. The trouble indicator is then immediately associated with the particular marker which is in trouble and a record is taken of the relays which cause the illumination of corresponding lamps, which may be labeled or colored in any convenient manner so as to identify the various pieces of apparatus and to show the condition of their operation. Thereafter the indicators immediately release from the marker. After the trouble man has taken a note of the trouble condition, he may extinguish the various lamps by manipulating a key, which unlocks the associated relays. The key 1840 serves this purpose in connection with the first indicator, while the key 2843 serves in connection with the second indicator.

It will also be obvious that the trouble indicators may serve in connection with the markers whether the call being handled is a local one or one involving interoffice trunks. For the purpose of brevity, it has not been considered necessary to show the establishment of an interoffice connection, but the functions of the markers in handling such connections are substantially the same.

30 What is claimed is:

1. The combination in a telephone system of switching apparatus for extending connections, a switch controlling mechanism for governing the operation of said apparatus, an indicating device, and means rendered effective if said mechanism fails to function for connecting said device to the controlling mechanism, said indicating device serving to indicate different degrees of progress made by such mechanism.

2. The combination in a telephone system of switching apparatus for extending connections, a switch controlling mechanism for governing the operation of said apparatus, an indicating device, and means rendered effective if said mechanism fails to operate properly for connecting said device to the controlling mechanism, said indicating device serving to indicate the relation of said mechanism to the switching apparatus and the various degrees of progress made at the time of failure.

3. The combination in a telephone system of selective switches for extending connections, a controlling mechanism associable with said switches for controlling the same, an indicating device for indicating different degrees of progress made by said mechanism and for identifying the switch-involved, and means responsive to a failure of said mechanism to proceed for connecting the indicating device to such mechanism.

4. The combination in a telephone system of selective switches for extending connections, a controlling mechanism associable

with such switches for governing the operation thereof, an indicating device, and means responsive to a failure of said mechanism to progress for connecting said device to such mechanism, said device serving to indicate the switch involved and the amount of progress made at the time of failure.

5. The combination in a telephone system of selective switches for extending connections, a controlling mechanism associable with said switches for governing the same, an indicating device for showing different degrees of progress made by said mechanism and for identifying the switch involved, and a time measuring device responsive to a failure of said controlling mechanism for causing the connection of said indicating device to such mechanism.

6. The combination in a telephone system of automatic switches for extending talking connections, a controlling mechanism associable with said switches for governing the operation thereof, a device for showing different degrees of progress made by said mechanism and for identifying the switch involved, a time measuring apparatus rendered effective in case said mechanism fails to operate properly, and means responsive to said measuring apparatus after a definite interval of time has expired for causing the connection of said device to the controlling mechanism.

7. The combination in a telephone system of selective switches for extending connections, a number of controlling mechanisms for governing said switches, a device for showing different degrees of progress made by said mechanisms, and means for automatically connecting said device to any one of said mechanisms.

8. The combination in a telephone system of selective switches for extending connections, a number of controlling mechanisms for governing said switches, an indicating device for showing different degrees of progress made by said mechanisms, for identifying said mechanisms and for identifying said switches, and means for automatically connecting said device to any one of said mechanisms.

9. The combination in a telephone system of selective switches for extending connections, a number of controlling mechanisms for governing said switches, a device for showing different degrees of progress made by said mechanisms, means for taking a controlling mechanism into use, means responsive to such mechanism when taken into use for connecting said device thereto, and means for releasing said mechanism.

10. The combination in a telephone system of selective switches for extending connections, a number of controlling mechanisms common to said switches arranged to record wanted designations and to se-

lectively control said switches, means for connecting one of such mechanisms to one of said switches, a device for showing different degrees of progress made by said mechanisms, and means for automatically connecting said device to the particular mechanism that has been connected to one of said switches.

11. The combination in a telephone system of a subscriber's line, selective switches for extending said line, a number of controlling mechanisms responsive to impulses transmitted over said line to record designations, means for connecting one of said mechanisms to one of said switches for selectively operating the same, an indicating device for indicating the progress made by said mechanisms, and means for automatically connecting such device to one of said mechanisms.

12. In a telephone system, selective switches for extending connections, a recording sender for storing designations, a plurality of markers common to said switches and to said sender, means for connecting said sender to an idle marker for controlling said marker, means for connecting such marker to one of said switches for selectively operating the switch, an indicating device common to all markers, and means for connecting the device to one of said markers for indicating the progress made by such marker.

13. In a telephone system, selective switches for extending connections, a number of recording senders for storing designations, a plurality of markers common to said switches and to said senders, means for connecting one of said senders to an idle marker for controlling such marker, means for connecting the marker taken into use to one of said switches for selectively operating the switch, an indicating device common to all markers, and means for con-

nected to the device to one of said markers for indicating the progress made by the marker and for identifying the sender and the marker.

14. In a telephone system, automatic switches for extending connections, a number of recording senders for registering designations, a plurality of markers common to said switches and to said senders, means for connecting a sender to one of said markers, means for connecting such marker to one of said switches for selectively operating the same, an indicating device common to all markers and senders, and means for connecting the indicating device to one of said markers for identifying the automatic switch through which the connection is being extended.

15. In a telephone system, automatic switches for extending connections, a number of recording senders, a plurality of markers common to said switches and to said senders, means for connecting one of said senders to an idle marker and for connecting the marker to one of said switches, an indicating device common to all markers, and means responsive to a failure of the marker to progress for connecting such device to the marker.

16. In a telephone system, a number of selective switches, each having vertical and horizontal rows of contacts for establishing connections, a switch controlling mechanism for governing the operation of said switches, an indicating device, and means rendered effective to connect said device to said controlling mechanism, said device serving to indicate the vertical and horizontal rows having the contacts through which the connection is being extended.

In witness whereof, I hereunto subscribe my name this 27th day of June A. D., 1924.

WARREN W. CARPENTER.
